CENTRIC BITE RELATOR

Harry Wilkinson, San Diego, Calif.

Application January 11, 1947, Serial No. 721,523

5 Claims. (Cl. 32—19)

1

My invention relates to a centric bite relator, more particularly for use in establishing centric relation of both condyle heads in the glenoid fossae in order to properly fit artificial dentures to an individual and the objects of my invention are:

First, to provide a centric bite relator of this class which greatly facilitates the accurate production of artificial dentures to fit an individual which has features normal to all the functioning positions of the patient's biting anatomy;

Second, to provide a centric bite relator of this class which aids the technician in producing properly fitting dentures with a minimum amount of trial and adjustment;

Third, to provide a centric bite relator of this class which aids in the production of artificial dentures which occlude perfectly throughout their entire biting surface;

Fourth, to provide a centric bite relator of this class which aids in the production of proper artificial dentures by substantially eliminating abnormal bite conditions of the patient caused by the loss of teeth which tend to assert themselves during the taking of an impression preliminary to making said artificial dentures;

Fifth, to provide a centric bite relator of this class which is very small and compact and readily and quickly connected to impression plates in a person's mouth; and

Sixth, to provide a centric bite relator of this class which is very simple and economical of construction, efficient in operation and which will not readily deteriorate or get out of order.

With these and other objects in view, as will appear hereinafter, my invention consists of certain novel features of construction, combination and arrangement of parts and portions as will be hereinafter described in detail and particularly set forth in the appended claims, reference being had to the accompanying drawing and to the characters of reference thereon forming a part of this application in which:

Fig. 1 is a top or plan view of my centric bite relator, Fig. 2 is a side elevational view thereof and Fig. 3 is a side elevational view of my centric bite relator shown in connection with impression plates for maintaining the same in spaced relation to each other in accordance with the normal retruded rest position of the condyle head.

Similar characters of reference refer to similar parts and portions throughout the several views of the drawing.

The screw 1, nut 2, attachment member 3 and

plate 4 constitute the principal parts and portions of my centric bite relator.

As shown best in Fig. 3 of the drawing, the screw 1 is provided with an enlarged attachment member 3 at its normally upper end and is provided with a longitudinally adjustable screw threaded nut 2 adapted to engage one side of the plate 4 when in connection with the upper and lower impression plates A and B, respectively, as shown by dash lines in Fig. 3 of the drawing. It will be noted that the plate 4 is freely moveable on the screw 1 and that the nut 2 provides means for forcing the plate 4 away from the attachment member 3 which is normally fixed to the upper impression plate A by means of wax or the like. The plate 4 bridges opposite sides of the impression plate B and supports the nut 2 in substantially the relationship as shown in Fig. 3 of the drawing.

20 The operation of my centric bite relator is substantially as follows:

The impression plates A and B are first prepared and the attachment member 3 is secured to the upper impression plate A in a centric location relatively thereto and said impression plates A and B are positioned in the patient's mouth and the nut 2 is adjusted longitudinally of the screw 1 until the spaced relationship of the impression plates A and B indicates a normal rest position of condyle heads of the patient. This normal rest position is taken preferably by measurement of the patient from a location at the intersection of the nose and upper lip to the lower portion of the patient's chin. This normal rest position is set up and very accurately maintained by the nut 2 resting on the plate 4 during very slight pressure being exerted thereon by the patient. After the normal rest position is set up, plaster is placed intermediate the impression plates A and B whereupon said impression plates A and B may be removed from the patient's mouth and transferred to a conventional articulator. In the use of my centric bite relator in producing artificial dentures the following conditions should be carefully considered.

The centric relation is the most retruded rest position from which lateral movement is possible and should not be confused with abnormal functioning positions which patients develop for themselves due to the partial loss of teeth preliminary to taking an impression bite. The tissue and bite surfaces of bite records should occlude perfectly throughout their entire length and the use of my centric bite relator obviates the difficulties encountered in attaining such results.

The plane of orientation and the occlusal plane is an imaginary plane and can be taken through the incisal contact point and the distal of the last molar for signifying the general direction of masticating surfaces in the denture space available. The acceptance of this plane permits more comprehensive alignment of articulation. The mandible functions in an arc providing it has no tooth interference and not limited or prevented by extreme overbites. The movements of the mandible are a combination of gliding movements and the chief movement is of the hinge character. Stability of the dentures depends upon the direction of force relatively to the seating surface thereof and to the equilibrium and balance of the supporting tissues. Set of the teeth should promote simple and precise function, maintain centric relation and give freedom to related movements of the mandible. Therefore it will be seen that balance of the dentures eliminates undue tissue changes and assures stability, thus the employment of my centric bite relator in the production of artificial dentures saves much time and promotes the production of accurately fitting dentures which are very efficient and comfortable.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. A centric bite relator comprising the combination of an impression, a plate bridging opposite sides of said impression and fixed thereto, a screw freely threaded in said plate, a nut adjustably screw-threaded on said screw and engageable with said plate, a second impression, one end of said screw provided with attachment means secured in centric relation with said second impression.

2. A centric bite relator comprising the combination of an impression, a bridge plate bridging opposite sides of said impression, said bridge plate having an opening substantially at the middle portion thereof, a screw extending through said opening having a head on one end and an attachment means on its opposite end, a nut arranged in screw-threaded relation to said screw and longitudinally of said screw engaging one side of said bridge plate, a second impression, said attachment means of said screw secured in centric relation with said second impression, whereby movement of said first and second impressions toward each other is limited by contact of said nut with said bridge plate.

3. A centric bite relator comprising the com-

bination of an impression, a bridge plate bridging opposite sides of said impression, said bridge plate having an opening substantially at the middle portion thereof, a screw extending through said opening having a head on one end and an attachment means on its opposite end, a nut arranged in screw-threaded relation to said screw and longitudinally of said screw engaging one side of said bridge plate, a second impression, said attachment means of said screw secured in centric relation with said second impression, whereby movement of said first and second impressions toward each other is limited by contact of said nut with said bridge plate, said attachment means being considerably larger in diameter than said screw.

4. A centric bite relator comprising the combination of an impression, a bridge plate bridging opposite sides of said impression, said bridge plate having an opening substantially at the middle portion thereof, a screw extending through said opening having a head on one end and an attachment means on its opposite end, a nut arranged in screw-threaded relation to said screw and longitudinally of said screw engaging one side of said bridge plate, a second impression, said attachment means of said screw secured in centric relation with said second impression, whereby movement of said first and second impressions toward each other is limited by contact of said nut with said bridge plate, said attachment means being considerably larger in diameter than said screw, and at the extremity thereof.

5. A centric bite relator comprising the combination of a pair of impression plates, a flat plate member having an opening therein substantially at the middle portion thereof, adapted to bridge opposite sides of one of said pair of impression plates, a screw freely movable in said opening having externally screw-threaded portions, a nut longitudinally adjustable on said externally screw-threaded portions and attachment means secured to the normally upper end of said screw, arranged to be fixed in centric relation with the other of said pair of impression plates, whereby longitudinal adjustment of said nut on said screw in engagement with said bridge plate maintains certain spaced relationship of said impression plates relatively to each other.
